UNITED STATES PATENT OFFICE.

WALTER V. TURNER AND WILLIAM M. CADY, OF EDGEWOOD, PENNSYLVANIA, ASSIGNEES TO THE WESTINGHOUSE AIR BRAKE COMPANY, OF PITTSBURGH, PENNSYLVANIA, A CORPORATION OF PENNSYLVANIA.

BRAKE-VALVE DEVICE.

1,078,020.

Specification of Letters Patent. Patented Nov. 11, 1913.

Application filed June 6, 1911. Serial No. 631,651.

To all whom it may concern:

Be it known that we, WALTER V. TURNER and WILLIAM M. CADY, citizens of the United States, residents of Edgewood, in the county of Allegheny and State of Pennsylvania, have invented a certain new and useful Improvement in Brake-Valve Devices, of which the following is a specification.

This invention relates to fluid pressure brakes, and more particularly to the type in which the brakes are applied by reducing the train pipe pressure and released by increasing the train pipe pressure.

The standard brake valve usually employed for controlling automatic brakes of the above character is provided with an equalizing reservoir and an equalizing discharge valve mechanism adapted upon a reduction in equalizing reservoir pressure to effect a discharge of air from the train pipe. Where a brake valve is provided at each end of the vehicle, so that the brakes may be controlled from either end of the car, if one brake valve is manipulated to reduce the train pipe pressure, it will be evident that the train pipe pressure is also reduced on the piston of the other equalizing valve mechanism, and as a consequence, fluid from the equalizing reservoir side of the piston is liable to leak past the piston to the train pipe side. The equalizing reservoir pressure is thus reduced and while this has no effect in making an application of the brakes, when the train pipe pressure is increased to release the brakes, the train pipe pressure being higher than the pressure in the equalizing reservoir, the equalizing piston is actuated by this higher train pipe pressure to open the train pipe discharge valve and vent air from the train pipe, thus retarding the increase in train pipe pressure, which of course delays the release of the brakes as well as wastes air by the undesired discharge of fluid from the train pipe.

The principal object of our invention is to provide improved means for preventing the above action of a brake valve not in use when another brake valve is manipulated to control the brakes.

In the accompanying drawing, Figure 1 is a diagrammatic view of a car brake equipment with our invention applied thereto; Fig. 2 a central sectional view of an engineer's brake valve embodying our improve-

ment; Fig. 3 a plan view of the rotary valve seat for the above brake valve; and Fig. 4 a face view of the rotary valve.

The brake valve may be of the usual standard construction comprising a casing 1, a rotary valve 2 contained in valve chamber 3 and adapted to be operated by a handle 4, an equalizing piston 5, having a chamber 6 on one side connected and subject to the pressure of an equalizing reservoir and having a chamber 7 on the opposite side which is adapted to be connected to the train pipe 8. The piston 5 operates a discharge valve 9 for venting fluid from the train pipe to the atmosphere.

Instead of connecting the chamber 7 directly to the train pipe in the usual manner, according to our invention, communication from the train pipe to said chamber is had only through ports and passages controlled by the rotary valve 2, and for this purpose, a passage 10 leads from the chamber 7 to the seat of the rotary valve and a passage 11 also leads from the train pipe to said seat. In the rotary valve 2 is provided a cavity 12 adapted to connect the passages 10 and 11 when the brake valve is in service application and lap positions and in all other positions of the brake valve said ports are disconnected.

In Fig. 1 a car brake equipment is shown comprising a train pipe 8 connected in the usual manner to a triple valve device 13, a brake valve being provided at opposite ends of the equipment.

It will now be evident that fluid from the train pipe only has access to the equalizing piston when the brake valve is in service application or lap positions or intermediate the two positions, so that if the brake valve is in any other position, variations in train pipe pressure made by another brake valve will not effect the piston 5 of the first brake valve.

It is customary, in brake valves for double ended service, to provide a single handle adapted to be removed only in a certain position of the brake valve, usually lap position, when it is desired to go from one end of the vehicle to the other. By locating this position in the present construction at a point where the passages 10 and 11 are disconnected it will be clear that when the handle is removed, communication will be

closed from the train pipe to the equalizing piston and consequently variations in train pipe pressure caused by manipulation of the other brake valve have no effect on the 5 equalizing piston of the brake valve not in use.

The above position is preferably located at a lap position such as that marked H in Fig. 3 of the drawing adjacent to the usual lap 10 position. Communication from the train pipe to the chamber 7 should be maintained in the usual service lap position, so as not to interfere with the proper action of the equalizing discharge valve mechanism when 15 the brake valve is turned from service application position to lap position.

Having now described our invention, what we claim as new and desire to secure by Letters Patent, is:—

20 1. In a fluid pressure brake, the combination with a train pipe, of a brake valve provided with an equalizing discharge valve mechanism and having a position for closing communication from the train pipe to said 25 equalizing discharge valve mechanism.

2. In a fluid pressure brake, the combination with a train pipe, of a brake valve and an equalizing discharge valve mechanism operated according to the opposing 30 pressures of the train pipe and the equalizing reservoir for controlling the discharge of air from the train pipe, said brake valve having a position for cutting off communication from the train pipe to the equalizing 35 discharge valve mechanism.

3. In a fluid pressure brake, the combination with a train pipe, of a brake valve and an equalizing discharge valve mechanism operated according to the opposing 40 pressures of the train pipe and the equalizing reservoir for controlling the discharge of air from the train pipe, said brake valve having means for establishing communication from the train pipe to said equalizing discharge 45 valve mechanism and having a position in which said communication is closed.

4. In a fluid pressure brake, the combination with a train pipe, of a valve for controlling the discharge of air from the train pipe, 50 a piston for operating said valve, and a manually operated valve for establishing communication from the train pipe to said piston both in service application and service lap positions and having a position for closing 55 said communication.

5. In a fluid pressure brake, the combination with a train pipe, of a valve for controlling the discharge of air from the train pipe, a piston subject to the opposing 60 pressures of an equalizing reservoir and the

train pipe for operating said valve, and a manually operated valve having a port for supplying fluid to the train pipe and adapted to establish communication from the train pipe to the train pipe side of said piston and having a position for closing said communication. 65

6. In a fluid pressure brake, the combination with a train pipe, of a valve for controlling the discharge of air from the train pipe, a piston subject to the opposing pressures of an equalizing reservoir and the train pipe for operating said valve, a handle, a valve operated by said handle for venting air from the equalizing reservoir and for 70 controlling communication from the train pipe to said piston, said valve having a position in which the handle is removable and in which said communication is closed. 75

7. In a fluid pressure brake, the combination with a train pipe, of a brake valve having associated therewith an equalizing discharge valve mechanism governed by the opposing pressures of the train pipe and an equalizing reservoir and having a manually 80 operated handle adapted to be removed in one position, and means for cutting off the train pipe from said equalizing discharge valve mechanism in said position. 85

8. In a fluid pressure brake, the combination with a train pipe, of a brake valve and an equalizing discharge valve mechanism subject to the opposing pressures of the train pipe and the equalizing reservoir, said brake valve having a service application position in which air is vented from the equalizing reservoir and communication is established from the train pipe to said equalizing discharge valve mechanism, and a handle for operating said brake valve and removable in a position in which said communication is cut off. 90 100

9. In a fluid pressure brake, the combination with a train pipe, of a brake valve provided with an equalizing discharge valve 105 mechanism and having a position for closing a passage, flow through which is necessary to the effective operation of the equalizing discharge valve mechanism, said passage being open to permit flow therethrough in 110 service application and service lap positions of the brake valve.

In testimony whereof, we have hereunto set our hands.
